(57) **ABSTRACT**

The invention relates to a sound broadcasting device comprising a high-frequency section including at least one high-frequency acoustic source (SHF), and a medium-frequency section including at least two medium-frequency sources (SMF), the acoustic sources (SHF, SMF) being vertically superposed, where the medium-frequency section comprises a lower sub-section, arranged below the high-frequency section and comprising at least one medium-frequency acoustic source (SMF), and an upper sub-section, arranged above the high-frequency section and comprising at least one medium-frequency acoustic source (SMF), where the vertical directivity of the high-frequency section has an incline, relative to the horizontal (H), that is substantially equal to the incline (θ_{MF}) of the vertical directivity of the medium-frequency section relative to the horizontal (H), so that the overall vertical directivity of the device has a non-zero incline (θ_{Dir}) relative to the horizontal (H).

SOUND BROADCASTING SYSTEM

RELATED APPLICATIONS

This present application is a National Phase entry of PCT Application No. PCT/FR2018/050060 filed Jan. 10, 2018, which claims priority to French Application No. 1750580 filed Jan. 24, 2017, the contents of each being incorporated herein by reference in their entireties.

TECHNICAL FIELD

This invention relates in general to the domain of professional or home sonorization. It is aimed particularly at a "column" sound diffusion system suitable for producing a high Sound Pressure Level (SPL) with a long range to be able to cover an extended audience, while maintaining high coherence/intelligibility.

BACKGROUND ART

It is known that sound can be produced by propagating a sound signal from an acoustic source such as a loudspeaker, possibly fitted with a sound box, or a loudspeaker enclosure containing several loudspeakers and/or sound boxes.

It is also known that the range can be increased and a large audience can be covered by using multiple acoustic sources within a sound diffusion device or system. The contributions of each acoustic source would be added correctly if all acoustic sources are located at a single point. In practice, this is impossible, because an acoustic source has a non-negligible volume.

Thus a stack of acoustic sources can give a higher sound pressure level (SPL) than the SPL produced by a single acoustic source. The vertical directivity of a vertical stack of acoustic sources has a narrowed and significantly elongated lobe. The vertical directivity is also higher than the vertical directivity of a single acoustic source, thus increasing the range and the audience volume covered. However, acoustic sources are not so easily added and the inevitable distances between acoustic sources produce interference that deteriorates coherence/intelligibility.

It is also known to be advantageous if the vertical directivity of a sound diffusion device has a slightly negative angle of inclination from the horizontal. For a sound diffusion device classically installed at a low height, this makes it possible firstly to cover a larger audience and secondly to avoid diffusion towards the ceiling which would constitute a loss of energy since there is no audience at the ceiling, and can cause unwanted reflections that can degrade intelligibility. A negative inclination of the vertical directivity is generally obtained by inclining the acoustic source or source or the sound diffusion device.

A narrow, elongated and advantageously inclined vertical directivity is required to increase the range. On the other hand, a large horizontal directivity is required, for example between 60 and 180°. To achieve this, it is advantageous to superpose acoustic sources in a vertical stack.

Another constraint for a sound diffusion system is its visual integration. To facilitate this visual integration, it is advantageous to have a system with the lowest possible visual footprint. This constraint combined with the previous constraint, make a "column" arrangement of acoustic sources advantageous.

SUMMARY

A sound diffusion system provides a compromise between apparently contradictory characteristics to increase the

2

sound pressure level, SPL, and the range, while maintaining a high coherence/intelligibility level.

This purpose is achieved by means of a sound diffusion system comprising a high-frequency section including at least one high-frequency acoustic source and a medium-frequency section comprising at least two medium-frequency acoustic sources, the acoustic sources being superposed vertically, in which the medium-frequency section comprises a lower subsection located below the high-frequency section and comprising at least one medium-frequency acoustic source and an upper subsection located above the high-frequency section and comprising at least one medium-frequency acoustic source, and in which the vertical directivity of the high-frequency section has an inclination from the horizontal approximately equal to the inclination of the vertical directivity of the medium-frequency section from the horizontal, such that the global vertical directivity of the device has a non-zero inclination from the horizontal.

According to another characteristic, the inclinations from the horizontal are negative.

According to another characteristic, the high-frequency section has a dissymmetric vertical wavefront.

According to another characteristic, the wavefront has a variable curvature, preferably increasing towards the bottom, and even more preferably continuously variable so as to form a "J".

According to another characteristic, the wavefront is conformed using a vertical waveguide integrating at least one high-frequency acoustic source, preferably all high-frequency acoustic sources.

According to another characteristic, the acoustic center of the lower subsection is set back from the acoustic center of the upper subsection by a distance such that an axis connecting the acoustic center of the lower subsection to the acoustic center of the upper subsection, has a misalignment angle from the vertical significantly equal to the inclination.

According to another characteristic, the medium-frequency acoustic sources of the lower subsection are aligned with each other along a first vertical axis and/or the medium-frequency acoustic sources of the upper subsection are aligned with each other along a second vertical axis.

According to another characteristic, the high-frequency section comprises a first number of high-frequency acoustic sources, preferably identical, the first number preferably being equal to 3.

According to another characteristic, at least one high-frequency acoustic source is a compression motor.

According to another characteristic, the lower subsection comprises a second number of medium-frequency acoustic sources and the upper subsection comprises a third number of medium-frequency acoustic sources, the medium-frequency acoustic sources preferably being identical and the absolute value of the difference between the second number and the third number is less or equal to 2 and the second number is preferably higher than the third number, also preferably the second number is equal to 4 and/or the third number is equal to 2, or the difference is zero.

According to another characteristic, the vertical wavefront is, at least partially, electronically conformed by processing of the sound signals sent to each of the high-frequency acoustic sources respectively.

According to another characteristic, at least part (Rb) of the setback is electronically simulated by delaying the sound signals sent to each of the medium-frequency acoustic

sources of the lower subsection and/or the upper subsection respectively, by a delay equal to the time taken by sound to travel along the setback part.

According to another characteristic, the device is integrated into a single "column" type loudspeaker enclosure.

Embodiments of the invention also relate to a sound diffusion system comprising a first sound diffusion device according to one of the preceding embodiments, a second sound diffusion device comprising a low frequency section and/or a very low frequency section.

According to another characteristic, the system also comprises a mechanical interface between the first device and the second device capable of allowing one of the devices, preferably the second device, to support the other device, with or without assembly, and/or an electric interface between the first device and the second device that can allow one of the devices, preferably the second device, to transmit sound signals and/or an electrical power supply to the other device.

BRIEF DESCRIPTION OF THE FIGURES

Other innovative characteristics and advantages of embodiments of the invention will become clear after reading the following description given purely for information purposes and in no way limitative, with reference to the appended figures among which:

FIG. 1a presents the directivity of an acoustic source, in the case of the horn type point source,

FIG. 1b presents the directivity, inclined downwards by an angle θ_{Dir} , obtained by inclining the source in FIG. 1a downwards by an angle $\theta_{Meca} = \theta_{Dir}$,

FIG. 2 presents a side view of a device according to prior art.

FIG. 3 presents a side view of a device according to embodiments of the invention,

FIG. 4 presents the vertical directivity of a medium-frequency acoustic source, in the case of the horn type point source,

FIG. 5 presents the vertical directivity of a superposition of medium-frequency acoustic sources similar to the source in FIG. 4,

FIG. 6 presents the vertical directivity of a superposition of high-frequency acoustic sources,

FIG. 7a presents the vertical directivity of the same superposition of high-frequency acoustic sources, provided with a plane waveguide,

FIG. 7b presents the vertical directivity, inclined downwards by an angle θ_{Dir} , obtained by inclining the device in FIG. 7a downwards by an angle $\theta_{Meca} = \theta_{Dir}$,

FIG. 8 presents the vertical directivity of the same superposition of high-frequency acoustic sources, provided with a dissymmetric waveguide with constant curvature,

FIG. 9 presents the vertical directivity of the same superposition of high-frequency acoustic sources, provided with a dissymmetric waveguide with variable curvature,

FIGS. 10a-b illustrate the function of a waveguide,

FIGS. 11a-b present the different types of waveguide,

FIG. 12 is a side view illustrating a preferred embodiment of a dissymmetric type waveguide with variable curvature, increasing towards the bottom and continuously variable, in "J" form,

FIG. 13 is a side view showing one embodiment of the device according to the invention,

FIG. 14 is a side view of another embodiment of the device according to the invention,

FIG. 15 is a perspective view showing one embodiment of the device according to the invention,

FIG. 16 is a perspective view illustrating a system according to an embodiment of the invention;

FIG. 17 is a perspective view illustrating the assembled system in FIG. 16;

FIGS. 18a-b are front and side views respectively illustrating one embodiment of the device.

For better clarity, identical or similar elements are represented with identical references on all figures.

DETAILED DESCRIPTION OF ONE EMBODIMENT

15 An acoustic source S, or a sound diffusion system 1 comprising several acoustic sources S, can be characterized by a directivity diagram containing a Sound Pressure Level (SPL) as a function of the position in space. This diagram typically contains nested 3d lobes, the SPL is significantly 20 constant within a lobe and decreases with increasing distance from the source S or the device 1. A section or projection in a horizontal or vertical plane shows horizontal or vertical directivity respectively.

FIG. 1a illustrates the vertical directivity of a single 25 acoustic source S, for example of the horn type point source. A point source type acoustic source radiates isotropically and has spherical directivity. A significantly conical shaped horn can restrict this directivity to an advantageously more restricted angular sector. An example of a horn point source 30 acoustic source S is the applicant's product X12. The directivity of such an acoustic source S has an acoustic axis A connecting the source S to the maximum SPL, approximately in line with the horizontal H. Thus, if an angle θ_{Dir} is defined as being the angle between the horizontal H and 35 the acoustic axis A representing the directivity of the source S, we can write the following, for FIG. 1a, $\theta_{Dir}=0$.

The acoustic source S can be inclined downwards by an 40 angle of inclination θ_{Meca} . The effect of this is to identically incline the directivity and the acoustic axis A by the same angle of inclination θ_{Meca} , as illustrated on FIG. 1b.

By convention, the source is shown at the left of all 45 directivity diagrams, and diffuses towards the right. The audience is spread over the entire width of the diagram, mainly concentrated horizontally at the bottom of the diagram. For guidance, the area of the diagram represents a 50 height of 5 m and a width/depth of 40 m. Each change in the grey shade corresponds to a reduction of 3 dB with increasing distance from the acoustic source S.

In order to diffuse a sound signal, an acoustic source S or 55 a sound diffusion system 1 is generally placed facing an audience, the acoustic axis A being significantly horizontal so that the lobe covers the audience. Comparing FIG. 1b with FIG. 1a shows that a slightly negative inclination θ_{Dir} of the acoustic axis A from the horizontal H is advantageous 60 in terms of the volume of audience covered and in terms of uniformity of the SPL. This is particularly true when the range is high. Furthermore, such a negative inclination θ_{Dir} prevents unwanted and/or prejudicial diffusion towards the ceiling.

In a sound diffusion system 1, it is classical to divide the 65 sound spectrum into frequency bands, and to dedicate one section including one or several acoustic sources to each frequency band. This makes it possible to make each section with one or several acoustic sources adapted to this frequency band.

One arbitrary but frequently used breakdown in the business consists of breaking down the sound spectrum as

follows, at least partially covering the spectrum audible to humans: 20 Hz-20 kHz, in three or four bands. A high-frequency HF band covers the highest frequencies, typically over a 1 kHz-20 kHz interval. A medium-frequency MF band covers intermediate frequencies, typically over a 200 Hz-1 kHz interval. A low frequency LF band covers the lowest frequencies, typically over a 50 Hz-200 Hz interval. Finally, an optional very low frequency VLF band covers the lowest frequencies, typically frequencies less than 50 Hz.

The device 1 according to a first embodiment of the invention proposed to cover the two top bands; the high-frequency band and the medium-frequency band. This sound diffusion device 1 comprises a high-frequency section 2 and a medium-frequency section 3, 4. The high-frequency section 2 comprises one or several high-frequency acoustic sources within a single high-frequency HF assembly. The medium-frequency section 3, 4 comprises several medium-frequency acoustic sources S_{MF} . Being a "column" device, all high-frequency and low frequency acoustic sources S_{HF} , S_{MF} are superposed vertically, without necessarily being aligned.

As illustrated in FIG. 2, classically in the above, and as confirmed by an analysis of products on the market, existing devices combine firstly all high-frequency acoustic sources within a single high-frequency HF assembly, and secondly all medium-frequency acoustic sources within a single medium-frequency MF assembly, and then puts the two HF, MF assemblies together. This is prejudicial in that, due to the non-negligible size of acoustic sources, the high-frequency acoustic center CHF is at a distance from the medium-frequency acoustic center CMF. Such an offset causes a degradation of the coherence/intelligibility of the sound.

According to one characteristic illustrated particularly in FIG. 3, this problem is solved by making a device 1 that separates the medium-frequency section into two subsections 3, 4 and arranging these two subsections 3, 4 on opposite sides of the high-frequency section 2. Thus, either one of the two subsections is placed below the high-frequency section 2 and is called the lower subsection 3, while the other subsection is placed above the high-frequency section 2 and is called the upper subsection 3.

As illustrated on FIG. 3, the result of such an arrangement is that the medium-frequency acoustic center C_{MF} resulting from the two subsections 3, 4 is located between the two subsections 3, 4, and may be close to or even advantageously coincident with the high-frequency acoustic center C_{HF} . This proximity of the high-frequency and medium-frequency acoustic centers C_{HF} and C_{MF} improves the coherence/intelligibility of the sound.

In order to diffuse sound with good coherence/intelligibility, it is convenient that the medium-frequency and high-frequency directivities are substantially superposed. To achieve this, it is desirable that the inclination θ_{HF} of the maximum high-frequency SPL of the vertical directivity of the high-frequency section 2 from the horizontal H, and the inclination θ_{MF} of the maximum medium-frequency SPL of the vertical directivity of the medium-frequency section 3, 4 from the horizontal H, are substantially equal. "Substantially equal" means that the absolute value of the difference between the inclination θ_{HF} and the inclination θ_{MF} is between 0° and 5°, and preferably between 0° and 2°.

A device 1 comprising a high-frequency section 2 surrounded by two medium-frequency subsections 3, 4, the two subsections 3, 4 and the high-frequency section 2 being significantly in line along a vertical axis, has a high-frequency vertical directivity derived from the high-frequency center C_{HF} and with a substantially zero high-frequency inclination θ_{HF} from the horizontal H and a

medium-frequency directivity derived from the medium-frequency center C_{MF} and having a significantly zero medium-frequency inclination θ_{HF} from the horizontal H. The two inclinations θ_{HF} , θ_{LMF} are thus significantly equal. The result is that the high-frequency and the medium-frequency directivities are significantly superposed.

As mentioned above, it is useful if the vertical directivity is at a negative inclination θ_{Dir} , so as to cover an audience, classically located lower down. According to a first embodiment, this inclination θ_{Dir} , that must be the same for the medium-frequency inclination θ_{MF} and for the high-frequency inclination θ_{HF} can be obtained by inclining the device 1 from the vertical v, by an angle θ_{Meca} . Advantageously, the inclination of the vertical directivities of the medium-frequency or high-frequency sources has an absolute value of between 1° and 30°.

The juxtaposition of acoustic sources S, in principle produces interference due to the inevitable separation between acoustic sources S. A rule used in standard practice indicates that the distance between two acoustic sources S can be neglected with regard to interference if this distance remains less than a magnitude that is an increasing function of the wavelength. Despite the fact that the dimension of acoustic sources reduces with reducing wavelength, this rule becomes increasingly difficult to respect as the wavelength reduces.

Considering the dimensions of envisaged medium-frequency acoustic sources S_{MF} , this rule can be respected for the medium-frequency section 3, 4, even when a high-frequency section 2 is intercalated, thus increasing the distance between medium-frequency acoustic sources S_{MF} . For information, it will be noted that in one preferred embodiment, the height of the high-frequency section is of the order of a few tens of cm.

It can be seen in FIGS. 4 and 5 that this rule is respected. FIG. 4 shows the vertical directivity of a single medium-frequency source S_{MF} . Comparatively, FIG. 5 shows the resulting vertical directivity for a stack of medium-frequency acoustic sources S_{MF} . Stacking several medium-frequency acoustic sources S_{MF} advantageously increases the resulting range. However no disturbance occurs, indicating that there is practically no interference.

On the other hand, considering the dimensions of available high-frequency acoustic sources S_{HF} , this rule can be difficult to respect for the high-frequency section 2. FIG. 6 shows the resulting vertical directivity for a stack of high-frequency acoustic sources S_{HF} , in this case three sources. Stacking several high-frequency acoustic sources S_{HF} advantageously makes the resulting range larger than for a single acoustic source. However, the disturbance of the diagram indicates an interference problem.

Failing acting on the cause, bringing the high-frequency acoustic sources S_{HF} closer can solve the interference problem and can be corrected by using a wave guide 5. A waveguide 5 is a device containing one or several acoustic sources S and designed to perform two functions. A first function is to eliminate interference by phasing said integrated acoustic sources, that then function like a single more powerful source. A second function is to conform the output sound wave front according to a given profile. The principle and the design of a waveguide invented by the applicant is described particularly in U.S. Pat. No. 5,163,167.

The action of a waveguide 5 is illustrated in FIGS. 10a-b. Three acoustic sources S are juxtaposed on FIG. 10a. The sources S, assumed to be point sources, each produce a spherical wavefront F. Each front F is centered on its source S. The fronts F are also mutually incoherent and potentially

the source of interference. On FIG. 10b, the same three sources S are combined using a waveguide 5. The produced wavefront F is unique.

A person skilled in the art will be able to design a waveguide 5 as a function firstly of acoustic sources S_{HF} and secondly of the required wavefront.

Thus, according to another characteristic, a waveguide 5 is advantageously used to eliminate the harmful consequences of interference at the high-frequency section 2.

A waveguide is improperly characterized by the shape of the wavefront that it produces. Thus for example, the waveguide 5 in FIG. 10b that conforms the wavefront F produced at the output in a plane is called a plane waveguide.

FIG. 7a illustrates the vertical directivity resulting from the vertical superposition of several high-frequency sources S_{HF} integrated in a plane waveguide 5. A comparison with FIG. 6 provides a measurement of the improvement made in terms of the homogeneity of the SPL produced and the increased range. Such a device can be inclined by an inclination θ_{Meca} so as to incline the directivity by the same inclination $\theta_{Dir} = \theta_{Meca}$, as illustrated in FIG. 7b. The benefit of the advantageous presence of such a waveguide 5 is obtained by using the waveguide 5 to conform the wavefront output from the high-frequency section 2, and therefore the high-frequency directivity, such that it optimizes the coverage of the audience.

Besides, according to another characteristic, the wavefront is dissymmetric. This dissymmetry that is accentuated downwards, introduces another embodiment to produce a negative high-frequency inclination θ_{HF} .

FIG. 11a illustrates an example of a waveguide symmetric about the horizontal H. FIG. 11b gives a comparative illustration of an example of a dissymmetric waveguide: the absolute value of the upper angle θ_2 is different from the absolute value of the lower angle θ_1 , and in this case is less than the lower angle θ_1 . This results in an equivalent dissymmetry of the wavefront.

Dissymmetry of the wavefront can be used to make a high-frequency inclination θ_{HF} of the vertical directivity, also advantageously negative, and thus replace an inclination of the high-frequency section 2 or the device 1. This advantageously makes it possible to keep a vertical layout for the high-frequency section 2 or the device 1, thus improving the visual footprint and facilitating architectural integration.

Alternatively, and particularly if the device 1 must be located higher and if it is required to increase the inclination θ_{Dir} of the global directivity of the device 1, an inclination obtained by dissymmetry of the wavefront can be combined with an inclination of the device 1, these two inclinations being additive.

The shape of the wavefront can be arbitrary and is advantageously described by a curvature. The curvature can be arbitrary. Thus, a constant curvature, produces a circular external surface.

FIGS. 11a-b illustrate the curvature of the waveguide 5 again. In the case of a constant curvature, the radius of curvature R1, R2 is constant and equal at all points. In the case of a variable curvature, the radius of curvature varies and R1 can be different from R2.

According to another characteristic, a variable curvature is advantageous in that it makes it possible to conform the directivity so that it can cover a large audience.

According to another preferred characteristic, the variation of the curvature is such that it increases downwards or, what is equivalent, that the radius of curvature reduces downwards. Thus, according to one preferred embodiment,

the curvature is continuously variable. The wavefront then has a "J" shape with a radius of curvature that reduces with increasing downwards distance.

Thus, FIG. 8 shows the vertical directivity obtained for a high-frequency section 2, with a dissymmetric wavefront with constant curvature. This directivity can be compared with that in FIG. 7b obtained with a device with a plane wavefront, to measure the improvement obtained, mainly in terms of homogeneity of the SPL achieved in the zone covered. Comparatively, all other things being equal, FIG. 9 shows the directivity obtained for a dissymmetric waveguide with variable curvature, the curvature increasing downwards. There is a significant increase in the range and homogeneity of the SPL.

FIG. 12 illustrates one possible embodiment of such a waveguide 5, dissymmetric with variable curvature, the curvature increasing downwards, continuously variable, so as to have a "J" shape.

Conformation of the wavefront, principally by means of its dissymmetry, make a negative high-frequency inclination θ_{HF} possible. An almost identical medium-frequency inclination θ_{MF} should be made so that the device 1 is balanced. As before, "almost identical" means that the absolute value of the difference between the inclination θ_{HF} and the inclination θ_{MF} is between 0° and 5°, and preferably between 0° and 2°.

To achieve this, and as illustrated in FIG. 13, according to another characteristic, the acoustic center C_{inf} of the lower subsection is set back relative to the acoustic center C_{sup} of the upper subsection 4, by a setback R. This setback R produces an inclination θ_{MF} of the medium-frequency directivity. Also, in order for the medium-frequency inclination θ_{MF} to be almost identical to the high-frequency inclination θ_{HF} obtained for the high-frequency section 2, the setback R should be such that an axis connecting the two subsections 3, 4, or more precisely the acoustic center C_{inf} of the lower subsection 3 to the acoustic center C_{sup} of the upper subsection 4, forms a misalignment angle θ_D from the vertical V approximately equal to the angle of inclination of the high-frequency directivity θ_{HF} . Thus, equality of the angles of inclination θ_{MF} , θ_{HF} , is confirmed. The result is that the high and medium-frequency vertical directivities are substantially superposed.

The layout of the medium-frequency acoustic sources S_{MF} within a subsection 3, 4 is a priori arbitrary. Preferably, an alignment of medium-frequency acoustic sources S_{MF} in a subsection 3, 4 is more efficient in terms of adding powers so as to obtain a high resulting SPL.

Thus, an ideal configuration for the sound produced is the configuration in which the medium-frequency acoustic sources S_{MF} within a subsection 3, 4 are aligned on the previously described axis connecting the acoustic centers C_{inf} and C_{sup} of subsections 3, 4. However, such a configuration increases the dimensions, mainly in depth, and degrades the visual footprint.

Besides, another configuration that does not significantly degrade the sound produced may be preferred. In this other configuration, the medium-frequency acoustic sources S_{MF} of the lower subsection 3 are aligned with each other along a first vertical axis. Alternatively or additionally, the medium-frequency acoustic sources S_{MF} of the upper subsection 4 are aligned with each other along a second vertical axis, that may be identical to the first. These configurations are advantageous in that they provide a low visual footprint and thus facilitate architectural integration.

There is no tight constraint on the position of subsections 3, 4 relative to the high-frequency section 2 along a hori-

zontal axis, in depth. It is preferable to not move them too far apart so as to not excessively separate the acoustic centers C_{HF} and C_{MF} , and also subsections 3, 4 are preferably aligned with the high-frequency section 2. According to one possible embodiment illustrated on FIG. 13, the upper subsection 4 is in line with the top of the high-frequency section 2, so as to limit the size of the device 1, in depth. This is also illustrated by the embodiment in FIG. 14.

The high-frequency section 2 comprises a first number n of high-frequency acoustic sources S_{HF} . This number n is related mainly to the required SPL at high-frequency, this level increasing with the number of high-frequency acoustic sources S_{HF} . A single high-frequency acoustic source S_{HF} is possible. It can be noted that a waveguide functions with a single acoustic source. The increase in the number of high-frequency acoustic sources S_{HF} could be prejudicial in that it increases the distance between the two subsections 3, 4. However, this prejudice remains low due to the small size typical of high-frequency sources S_{HF} . FIG. 3, 13-14 or 18a-b, illustratively show a high-frequency section 2 comprising two, three or four high-frequency acoustic sources S_{HF} and the height may then be of the order of 20 to 40 cm. Advantageously, but without any obligation, these high-frequency acoustic sources S_{HF} are identical. According to one preferred embodiment, the first number n of high-frequency acoustic sources S_{HF} of the high-frequency section 2 is equal to 3. Preferably, this first integer number n is within the interval [2; 5].

The search for a high SPL, including for the high-frequency section 2, and in a small integration volume, leads to the preferred use of at least one compression motor to make one or several high-frequency sources S_{HF} , due to the advantageously high power density provided by such a component.

The lower subsection 3 comprises a second number m of medium-frequency acoustic sources S_{MF} and the upper subsection 4 comprises a third number p of medium-frequency acoustic sources S_{MF} . The total number m+p is related mainly to the required SPL level at medium-frequency, this level increasing with the total number of medium-frequency acoustic sources S_{MF} . This SPL level is preferably coherent with the SPL level at high-frequency. A single medium-frequency acoustic source S_{MF} in one or both of the two subsections 3, 4 is possible. The increase in the number of medium-frequency acoustic sources S_{MF} is only prejudicial in that it increases the height and therefore the size of the device 1. According to one preferred embodiment, the medium-frequency section comprises 6 medium-frequency acoustic sources S_{MF} : the second number m of medium-frequency acoustic sources S_{MF} of the upper subsection 4 is equal to 2 and the third number p of medium-frequency acoustic sources S_{MF} of the lower subsection 3 is equal to 4. Preferably, the second integer number m is within the interval [1; 5], and the third integer number p is within the interval [2; 6].

According to the previous embodiment, comprising 6 medium-frequency acoustic sources S_{MF} , combined with a high-frequency section 2 comprising 3 high-frequency acoustic sources Sur, to achieve an illustrative SPL of the order of 130 dB, the height of a medium-frequency acoustic source S_{MF} is of the order of 13 cm and the height of a high-frequency acoustic source S_{HF} is of the order of 8 cm. The result is that the height of the device 1 is advantageously less than 1.30 m, thus facilitating handling.

With regard to interference, it has been seen that the distance between two juxtaposed adjacent acoustic sources must remain less than a magnitude that is an increasing

function of the wavelength. This constraint is much less severe for medium frequencies than for high frequencies. This makes it possible to separate the medium-frequency section into two subsections 3, 4. This also avoids the need to use a waveguide 5 for medium frequencies.

Any arbitrary distribution of medium-frequency acoustic sources S_{MF} between the two subsections 3, 4 is possible. Ideally, for the medium-frequency acoustic center C_{MF} to be as close as possible to the high-frequency acoustic center C_{HF} , an equilibrium, namely a second number m equal to the third number p is preferred. FIG. 13 illustratively shows a balanced lower subsection 3 and upper subsection 4 each comprising three medium-frequency acoustic sources S_{MF} .

However, a slight unbalance is acceptable. A difference with an absolute value less than or equal to 2 between the second number m of medium-frequency acoustic sources S_{MF} in the upper subsection 4 and the third number p of medium-frequency acoustic sources S_{MF} in the lower subsection 3 is acceptable. The most "voluminous" subsection can be either the lower subsection 3 or the upper subsection 4, whichever is preferred.

According to one preferred embodiment, more particularly illustrated in FIG. 14, the lower subsection 3 is preferred, for example with one or as illustrated with two, 25 additional acoustic sources. This causes the medium-frequency acoustic center C_{MF} to be slightly separated from the high-frequency acoustic center C_{HF} but however the consequences of this can be neglected. However, advantageously, this makes it possible to raise the average diffusion axis, 30 passing approximately through the middle of the acoustic centers C_{MF} , C_{HF} of the device 1, so as to adapt it to the listening height of the audience. This is particularly advantageous for a placed device 1.

Advantageously, but without any obligation, the medium- 35 frequency acoustic sources S_{MF} are identical. Identity may lie within a subsection 3, 4, or it can be global.

According to a first embodiment, the wavefront can be conformed mechanically using a waveguide 5. The waveguide 5 is then a frame specifically conformed to form the 40 required wavefront and holding the acoustic sources and imposing a position and a relative orientation on them.

According to another technical characteristic, the wavefront is electronically conformed by processing of sound signals sent to each of the high-frequency acoustic sources S_{HF} respectively. This electronic conformation can be partial 45 or total.

In the case of a fully electronic conformation of the wavefront, electronic conformation entirely replaces the 50 mechanical waveguide 5 and electronically fixes the relative position and orientation of the acoustic sources S_{HF} . In this case, the curvature imposed by the waveguide 5 on the acoustic sources S_{HF} no longer serves any purpose. This then makes it possible to have several, and advantageously all high-frequency acoustic sources S_{HF} of the high-frequency section 2 in a chosen layout, for example aligned 55 with each other, and preferably aligned along a vertical axis. This characteristic can optimize the reduction in the visual footprint.

In the case of a partially electronic conformation of the 60 wavefront, a mechanical waveguide 5 is used. Electronic processing then completes shaping of the wavefront produced mechanically by the waveguide 5, to accentuate or reduce the curvature.

It has been seen that the vertical directivity in medium-frequency was inclined downwards by means of a setback R applied to the lower subsection 3 relative to the upper subsection 4. According to a first embodiment, this setback

11

R can be applied geometrically by physically moving the lower subsection 3 backwards. Thus, with medium-frequency acoustic sources Sr with a height of the order of 13 cm, a setback of the order of 40 cm can give an inclination θ_{MF} of the vertical directivity at medium-frequency of -3° .

According to another embodiment this setback 4 can be made partially or entirely electronically. This requires processing of sound signals sent to each of the medium-frequency acoustic sources S_{MF} of the lower subsection 3 and/or the upper subsection 4.

A setback R is made by retarding sound signals sent to medium-frequency acoustic sources S_{MF} that are to be setback, namely those in the lower subsection 3. The applied delay T then corresponds to the time necessary for sound to travel the distance R. Application of such a relative delay T between the lower subsection 3 and the upper subsection 4 then makes it possible to geometrically align the two subsections 3, 4 or more precisely, their acoustic centers C_{inf} and C_{sup} respectively along a vertical axis. This characteristic is advantageous in terms of the visual footprint of the device 1 and architectural integration.

According to a mixed embodiment, a first part Ra of the setback R is made geometrically by effectively setting back the acoustic sources S_{MF} by a distance Ra, while a second part Rb of the setback R is made electronically by retarding the sound signals by a delay corresponding to the time necessary for sound to travel the distance Rb. The two parts are added together to form the setback: $Ra+Rb=R$.

Each medium-frequency acoustic source S_{MF} can be electronically controlled individually. However, electronic processing means are expensive. In one particular advantageous embodiment, a single electronic processing comprising a fixed delay is applied to the sound signals of medium-frequency acoustic sources S_{MF} of the lower subsection 3, so as to reduce the number of these processing means. If the delay corresponds to the setback R, the acoustic sources of the lower subsection 3 can be vertically aligned with the upper subsection 4.

The device 1 as described above can be made in different manners. Thus, it can be made by a modular assembly from elements in a kit. According to one preferred embodiment, it is advantageously integrated into a single speaker enclosure.

The device 1, as described above, diffuses high frequencies and medium frequencies. The device 1 is advantageously completed by a second sound diffusion device 7 comprising a low frequency section and/or a very low frequency section 9, so as to constitute a system capable of covering the entire audible sound spectrum.

Such an embodiment separating the low and/or very low frequency is advantageous in that the volume, and therefore the lateral dimension and depth of an acoustic source increases as the frequency drops. Also, a low frequency and very low frequency acoustic source, although it controls the width/depth of a system over its entire height, results in a very wide system with a strong visual impression.

Separating firstly the medium and high-frequency and secondly the low and/or very low frequency makes it possible to make a system as illustrated on FIG. 16, with a very much smaller visual impression, at least for device 1.

Making the diffusion system in two devices 1, 7 is also advantageous in terms of architectural integration. The second device 7 is typically placed on the floor or on a stage. The first device 1 can advantageously be suspended independently, as illustrated in FIG. 15.

Alternatively, if it is required to have a single-piece diffusion system, the two devices 1, 7 can be combined.

12

According to one embodiment, illustrated more particularly in FIG. 16, the devices 1, 7 comprise an interface means 8 such as male/female interfaces placed on one or the other or distributed on both of the first device 1 and the second device 7, 9.

This interface means 8 advantageously comprises a mechanical interface means that will enable one of the devices 1, 7, to support the other device. Allowing for the relative masses, the second device 7 is preferably the device 10 that supports the first device 1 and therefore that integrates the mechanical interface. This assembly can be made with or without assembly at the interface. The result of the combination of a first device 1 and a second device 7 is illustrated in FIG. 17. According to this embodiment, this mechanical interface means can enable devices 1, 7 to engage one in the other.

The interface device 8 also advantageously comprises an electric interface means that can enable one of the devices 1, 7, to transmit sound signals and/or electrical power supply 20 to the other device, so that it is only necessary to connect the system to the control center once.

FIGS. 18a-b show a front view and a side view respectively of one embodiment of the device 1. In this case, the upper subsection 4 comprises two medium-frequency acoustic 25 sources S_{MF} and the lower subsection 3 comprises four medium-frequency acoustic sources S_{MF} . The high-frequency section 2 comprises three high-frequency acoustic sources S_{HF} and a waveguide 5 with a continuously variable curvature with a "J" shape.

The invention is described above as an example. It is understood that one skilled in the art will be able to make different variant embodiments of the invention, for example by combining the different characteristics described above taken alone or in combination, without going outside the framework of the invention.

The invention claimed is:

1. A sound diffusion device comprising a high-frequency section including at least one high-frequency acoustic source (S_{HF}) and a medium-frequency section comprising at least two medium-frequency acoustic sources (S_{MF}), the acoustic sources (S_{HF} , S_{MF}) being superposed vertically;

wherein the medium-frequency section comprises a lower subsection located below the high-frequency section and comprising at least one medium-frequency acoustic source S_{MF} and an upper subsection located above the high-frequency section and comprising at least one medium-frequency acoustic source S_{MF} , and in that the vertical directivity of the high-frequency section has an inclination (θ_{HF}) from the horizontal (H) approximately equal to the inclination (θ_{MF}) of the vertical directivity of the medium-frequency section from the horizontal (H), such that the global vertical directivity of the device has a non-zero inclination (θ_{Di}) from the horizontal (H);

the high-frequency section also has a dissymmetric vertical wavefront; and the acoustic center (C_{11}) of the lower subsection is set back from the acoustic center (C_{sup}) of the upper subsection by a distance (R) such that an axis connecting the acoustic center (C_{11}) of the lower subsection to the acoustic center (C_{sup}) of the upper subsection, has a misalignment angle (θ_D) from the vertical (V) significantly equal to the inclination (θ_{HF}).

2. A device according to claim 1, wherein the inclinations (θ_{HF} , θ_{MF}) from the horizontal (H) are negative.

3. A device according to claim 1, wherein the wavefront has a variable curvature.

13

4. A device according to claim 1, wherein the vertical wavefront is conformed using a vertical waveguide integrating at least one high-frequency acoustic source (S_{HF}).

5. A device according to claim 1, wherein the vertical wavefront is at least partially electronically conformed by processing of the sound signals sent to each of the high-frequency acoustic sources (S_{HF}).

6. A device according to claim 1, wherein at least part (Rb) of the setback (R) is electronically simulated by delaying the sound signals sent to each of the medium-frequency acoustic sources (S_{MF}) of the lower subsection and/or the upper subsection, by a delay equal to the time taken by sound to travel along the part (Rb) of the setback (R).

7. A device according to claim 1, wherein the medium-frequency acoustic sources (S_{MF}) of the lower subsection are aligned with each other along a first vertical axis and/or the medium-frequency acoustic sources (S_{MF}) of the upper subsection are aligned with each other along a second vertical axis.

8. A device according to claim 1, wherein the high-frequency section comprises a first number (n) of high-frequency acoustic sources (S_{HF}).

9. A device according to claim 8, wherein at least one high-frequency acoustic source (S_{HF}) is a compression motor.

10. A device according to claim 1, wherein the lower comprises a second number (m) of medium-frequency acoustic sources (S_{MF}) and the upper subsection comprises a third number (p) of medium-frequency acoustic sources (S_{MF}), the medium-frequency acoustic sources (S_{MF}) being

14

identical and the absolute value of the difference between the second number (m) and the third number (p) is less than or equal to 2 and the second number (m) is more than the third number (p), also the second number (m) is equal to 4 and/or the third number (p) is equal to 2, or said difference is zero.

5 11. A device according to claim 1, integrated in a single "column" type of enclosure.

12. A sound diffusion system, comprising a first sound diffusion device according to claim 1, and a second sound diffusion device comprising a low frequency section or a very low frequency section.

10 13. A system according to claim 12, also comprising a mechanical interface between the first device and the second device capable of allowing one of the devices, to support the other device, and/or an electric interface between the first device and the second device that can enable one of the devices, to transmit sound signals and/or an electrical power supply to the other device.

14. A device according to claim 3, the variable curvature 20 increasing downwards.

15 15. A device according to claim 14, the variable curvature being continuously variable so as to form a "J".

16. A device according to claim 8, the first number (n) of high-frequency acoustic sources (S_{HF}) being identical.

25 17. A device according to claim 8, the first number (n) being equal to 3.

18. A sound diffusion system, comprising a first sound diffusion device according to claim 1, and a second diffusion device comprising a low frequency section and a very low frequency section.
